FLOOR POLISHER

Joseph Palma, Jr., Berwyn, Ill., assignor to S. C.
Johnson & Son, Inc., Racine, Wis.

Application December 8, 1949, Serial No. 6,509

Term of patent 14 years

(Cl. D9—2)

To all whom it may concern:

Be it known that I, Joseph Palma, Jr., a citizen of the United States, residing at Berwyn, in the county of Cook and State of Illinois, have invented a new, original, and ornamental design for a Floor Polisher, of which the following is a specification, reference being had to the accompanying drawing, forming part thereof.

Figure 1 is a perspective view of a floor polisher, showing my new design.

Figure 2 is a top plan view of the polisher shown in Figure 1 with the handle support parallel to the base.

Figure 3 is a front elevational view of the polisher shown in Figure 1.

Figure 4 is a rear elevational view of the polisher shown in Figure 1.

The side not shown is substantially the same as the one shown in Figure 3.

I claim:

The ornamental design for a floor polisher, as shown and described.

JOSEPH PALMA, JR.
